WILLIAM REETZ, OF CHICAGO, ILLINOIS, ASSIGNOR TO UNIVERSAL AUTO SUPPLY
MANUFACTURING COMPANY, OF CHICAGO, ILLINOIS.

MUFFLER FOR AUTOS.

1,109,702.

Specification of Letters Patent. Patented Sept. 8, 1914.

Application filed September 25, 1913. Serial No. 791,694.

To all whom it may concern:

Be it known that I, WILLIAM REETZ, a citizen of the United States, residing at Chicago, in the county of Cook and State of Illinois, have invented certain new and useful Improvements in Mufflers for Autos, of which the following is a specification.

The essential object of this invention is to provide a muffler for explosive engines by which the successive bodies or volumes of air or heated gases delivered from the engine are emitted from the muffler in a practically continuous stream.

In the drawings, Figure 1 is an interior view of the muffler, one of the casing members being removed; Fig. 2 is an elevation taken at right angles to the view of Fig. 1; Fig. 3 is a detailed sectional view of the hub of the fan, showing the arrangement for mounting the blades in position; Fig. 4 is a view similar to Fig. 3, the members which clamp the blades in position being removed; and Fig. 5 is a detail of Fig. 4, looking toward the left from the line 5—5, Fig. 4.

The operating parts are held or retained within a casing formed of the two parts 1 and 2, which members are both provided with ears 3 perforated at 4, bolts 5 being adapted to pass through the perforations and clamp the members 1 and 2 together.

At the left end, the casing is formed with an enlargement 6 within which the fan 7 is received. Said fan is carried upon the shaft 8, which shaft is journaled in one of the casing members. The blades of the fan are narrower at the ends than they are near the hub, said wider portions of the blades being designated 9. Upon the shaft 8 the screw 10 is secured, said screw being toward the right of the enlargement 6 and at a point where the casing is cylindrical in shape. The exhaust pipe 11 from the engine enters the enlargement 6 near the bottom, Fig. 2, and the conduit 12 connects the interior of the recess or cavity 13 within which the blades of the fan are adapted to move to that cylindrical part or section 14 of the casing within which the screw 10 is received. As the heated and escaping gases from the engine pass through the pipe 11, traveling

in the direction of the arrows, the gases will strike the blades 7 of the fan, thus causing the fan to revolve. As the fan revolves, it being obvious that its revolution is caused by the pressure of the exhausting gases, the gases will pass around in the recess 13 until they reach the conduit 12, it being understood that the gases must travel through about 270 degrees of arc in passing from the discharge end of conduit 11 to the receiving end of conduit 12. After the gases have passed through the conduit 12 and into that part of the casing designated 14, the gases will thus be somewhat further checked by the screw 10, and by the time that the gases have reached the right end, the action of the fan blades 7 and the threads of the screw 10 will have been such as to have converted the successive bodies of gases which entered the conduit 11 into a continuously flowing stream which escapes at the discharge end on the right, Figs. 1 and 2.

As previously stated, the blades of the fan are wider near the hub than they are at their extremities, and the recess or cavity 13 which is within the enlargement 6 is shaped so as to conform to the shape of the fan, the recess or cavity 13 being wider near the center, as indicated at 15, than it is at the ends.

As best shown in Fig. 2, the gases from the engine first engage the blades of the fan near their outer ends where they are relatively narrow and there act upon the fan so as to cause rotation of the same and of the shaft 8 upon which the fan is secured, but when the gases reach the enlarged part or section 15 of the opening 13, said gases expand in volume, and this expansion tends to create a draft or suction which assists in the removal of the gases from the engine. Were the fan to be positively driven from a suitable source of power, the fan itself would create the suction, but since the fan in this invention is driven by the escaping gases, the desired suction is due to the provision of the enlarged recess 15.

It would be possible to construct the fan of a single integral casting, but it is preferable for many reasons to make same of a plurality of parts assembled together. The

hub 16 which encircles the left end of the shaft 8 is a cylindrical member provided with slots or recesses 17. The inner ends of the blades 7 are formed, as best shown in Fig. 3, with the recesses 18 upon each side, said recesses 18 being wedge-shaped so as to receive the beading 19 upon the caps 20. The two caps 20 one of which is shown detached from the hub 16 in Fig. 4 and attached thereto in Fig. 3, clamp the blades in place when in the position of Fig. 3, and because of the reception of the beads 19 within the recesses 18 hold the blades 7 firmly in place. The shaft itself is journaled in supports secured to the casing 1. Near one end is the block or journal 22, and at the opposite end is the journal 23 hollowed out at 24 so as to receive the projecting end of the shaft 8. At its right end, the casing carries the funnel or delivery device 25 (shown conventionally), and the pipe 26 through which the gases pass into the atmosphere may be in any desired position or lead to any desired exit. An additional bearing 25 for the shaft 8 arises from the fact that the casing members are grooved at 27.

From Fig. 1 of the drawings it will be seen that the conduit 11, through which the gases from the engine pass, is provided with 30 a bend or elbow 28. The gases, therefore, do not enter the chamber within which the fan rotates in a line parallel to the axis of the fan, but are directed at such an angle to the axis as to strike the blades perpendicularly. 35 Because of this construction, the fan will be driven with a greater degree of certainty and at a greater speed than would be the case, if the exhaust gases from the engine passed into the fan chamber parallel to the 40 axis of the shaft 8.

It will be obvious that many changes in the details of construction and arrangement of parts may be made without departing from the scope of the invention.

45 I claim as my invention:

1. A muffler comprising a casing, an enlarged part upon said casing, a fan within said enlargement, a shaft upon which said fan is mounted, said shaft being journaled in 50 the casing, and a worm or screw upon said shaft, there being a conduit intermediate the engine and the enlarged part of said casing, and a conduit extending from said worm to said enlargement, said worm being of substantially the same diameter as that part of the casing within which the worm is received.

2. A muffler comprising a casing formed with an enlargement, a fan received within 60 said enlarged part, a worm received within the casing, a shaft upon which both said worm and said fan are secured, a conduit leading from the engine and entering said enlarged part, and a conduit leading from

said enlarged part and adapted to convey 65 the gases from said enlarged part to said worm, said worm being of substantially the same diameter as that part of the casing within which the worm is received.

3. A muffler comprising a casing formed 70 with an enlargement, a fan received within said enlarged part, a worm received within the casing, a shaft upon which both said worm and said fan are secured, a conduit leading from the engine and entering said 75 enlarged part, and a conduit leading from said enlarged part and adapted to convey the gases from said enlarged part to said worm, the cavity within which said fan moves being larger near the hub than near 80 the outer extremities of the blade of the fan.

4. A muffler comprising a casing formed with an enlargement, a fan received within 85 said enlarged part, a worm received within the casing, a shaft upon which both said worm and said fan are secured, a conduit leading from the engine and entering said enlarged part, and a conduit leading from 90 said enlarged part and adapted to convey the gases from said enlarged part to said worm, said fan being provided with blades which are relatively wide at or near the hub but narrower at their extremities.

5. A muffler comprising a hollow casing 95 made in sections, means for securing said sections together, said sections being formed with an enlarged cavity at one end and with a cylindrical cavity, there being a conduit intermediate said cylindrical cavity and the cavity formed by said enlargement, a conduit in connection with said enlargement and adapted to convey the gases from the engine thereinto, a shaft, a worm thereupon within said cylindrical part of said casing, and a 100 fan thereupon within said enlargement, said fan having blades relatively wide near the hubs and relatively narrow at their extremities, and means for supporting said shaft.

6. A muffler comprising a casing formed 110 with an enlargement, a fan received within said enlarged part, a worm within the casing, a shaft upon which both said worm and said fan are secured, a conduit leading from the engine and entering said enlarged part, 115 said conduit being arranged with its discharge end obliquely disposed to the axis of said shaft, and a conduit leading from said enlarged part and connecting said enlarged part to that part of the casing within which 120 said worm is received.

7. A muffler comprising a casing formed with an enlargement, a fan received within 125 said enlarged part, a worm within the casing, a shaft upon which both said worm and said fan are secured, a conduit leading from the engine and entering said enlarged part, said conduit being arranged with its dis-

charge end obliquely disposed to the axis of
said shaft, and a conduit leading from said
enlarged part and connecting said enlarged
part to that part of the casing within which
said worm is received, said fan being pro-
vided with blades which are wider at or near
the hub than at their outer extremities.

In testimony whereof I hereunto affix my
signature in the presence of two witnesses.

WILLIAM REETZ.
